US0D1087512S

(12) **United States Design Patent** (10) **Patent No.:** **US D1,087,512 S**
(45) **Date of Patent:** **** Aug. 5, 2025**

(54) **BROOM HANDLE**

(71) Applicant: **George M. Kelly**, Dorchester, MA (US)

(72) Inventor: **George M. Kelly, Jr.**, Dorchester, MA (US)

(73) Assignee: **George M. Kelly, Jr.**, Dorchester, MA (US)

(**) Term: **15 Years**

(21) Appl. No.: **29/905,601**

(22) Filed: **Oct. 23, 2023**

Related U.S. Application Data

(62) Division of application No. 29/776,690, filed on Mar. 31, 2021, now Pat. No. Des. 1,002,981.

(57) **CLAIM**

The ornamental design for a broom handle, as shown and described.

DESCRIPTION

FIG. 1 is an environmental perspective view showing broken-line environmental items with the broom handle according to a second embodiment;

FIG. 2 an upper perspective view thereof;

FIG. 3 is a lower perspective view thereof;

FIG. 4 is a front view thereof, the front view being the same as the rear view thereof, the left side elevation view thereof, and the right side elevation view thereof;

FIG. 5 is a top view thereof; and,

FIG. 6 is a bottom view thereof.

The broken lines show environmental items and portions of the broom handle that form no part of the claimed design.

1 Claim, 5 Drawing Sheets
